UNITED STATES PATENT OFFICE

155,407

DESIGN FOR A DISPLAY CASE

Roy L. Flannery, Chicago, Ill., assignor to The Boye Needle Company, Chicago, Ill., a corporation of Illinois

Application February 17, 1948, Serial No. 144,552

Term of patent 14 years

(Cl. D80—11)

To all whom it may concern:

Be it known that I, Roy L. Flannery, a citizen of the United States, residing at Chicago, county of Cook, and State of Illinois, have invented a new, original, and ornamental Design for a Display Case, of which the following is a specification, reference being had to the accompanying drawing, forming a part thereof, in which:

Figure 1 is a top plan view of a display case, showing my new design; Fig. 2, a perspective view of a half-section of the case; and Fig. 3, a front elevational view of the display case shown in Fig. 1.

I claim:

The ornamental design for a display case, as shown.

ROY L. FLANNERY.
